UNITED STATES PATENT OFFICE.

EDWARD E. PINKERTON, OF SIOUX CITY, IOWA.

DESIGN FOR A BOX-BLANK.

SPECIFICATION forming part of Design No. 32,375, dated March 20, 1900.

Application filed February 16, 1900. Serial No. 5,538. Term of patent 14 years.

To all whom it may concern:

Be it known that I, EDWARD E. PINKERTON, a citizen of the United States, and a resident of Sioux City, in the county of Woodbury and 5 State of Iowa, have invented and produced a new and original Design for a Box-Blank, of which the following is a full, clear, and exact description.

Reference is to be had to the accompanying 10 drawing, forming a part of this specification, in which the figure is a face view of a box-blank, showing my design.

The design in its entirety consists of an approximately-rectangular middle piece A, 15 flanked by similarly-shaped sides B B' and terminating at its ends in flaps C C', having slits C² extending inwardly from the outer edge to divide the outer portion of each flange C C' into hook-shaped members C³ C⁴, the side 20 edges of the flaps C C' being curved and a distance away from the inner side edges of the flaps D D' appearing on the ends of the sides B B', respectively, said flaps D D' appearing each near its outer side edge with an

elongated slot D², parallel with the said outer 25 edge, a tongue D⁵ extending into the slot, the sides D⁴ of the tongue extending obliquely in an inward direction, and the middle piece A, the sides, and the several flaps appearing with crease-lines E at the junctions of the several 30 parts.

The leading features of the design consist of the middle piece having the slitted end flaps and hooks and flanking sides having slotted end flaps, as shown. 35

Having thus fully described my invention, I claim as new and desire to secure by Letters Patent—

The design for a box-blank, as herein shown and described. 40

In testimony whereof I have signed my name to this specification in the presence of two subscribing witnesses. 40

EDWARD E. PINKERTON.
